UNITED STATES PATENT OFFICE.

FRED. B. WALKER AND JAMES LAUDER, OF GALVESTON, TEXAS.

RAILWAY STEAM CAR-BRAKE.

SPECIFICATION forming part of Letters Patent No. 278,297, dated May 22, 1883.

Application filed January 12, 1883. (No model.)

To all whom it may concern:

Be it known that we, FRED. B. WALKER, a citizen of the United States, and JAMES LAUDER, a subject of the Kingdom of Great Britain, residing at Galveston, county of Galveston, State of Texas, have invented a new and useful Improvement in Railway-Car Brakes, of which the following is a full, clear, and exact description thereof, reference being had to the accompanying drawings, making part of this specification.

Our invention relates to an improvement in car-brakes; and it consists in combining with a car-brake of suitable construction a steam actuating device attached to the locomotive and provided with a valve of peculiar construction and operation, whereby in the event of an accident to the machinery serious consequences would be avoided, as will be more fully set forth hereinafter.

In the accompanying drawings, Figure 1 is a top plan view of a tender, partly broken away, with our improved attachment. Fig. 2 is a vertical longitudinal section of the same. Fig. 3 is a detailed view of the mechanism attached to the locomotive.

a represents a cylinder fastened under the deck of an engine and in a line and directly behind the rear driving-axle. In the cylinder *b* plays a piston, the rod *b* of which has at its outer end an eye, *c*, by which it can be connected to the rod *B* under the front end of the tender. This rod *B* extends the length of the tender, and is pivoted at its center to the rod *C*, pivoted to one side of the tender-frame, the outer end being pivoted to the rod *D*, which extends a little beyond the rear end of the tender. The rod *B* is also provided near its rear end with the elongated slot *B'*, into which projects the upper end of the pivoted lever *E*, secured to the brakes at *e* and connected to the front brakes of the truck by the rod *F*, pivoted thereto. When steam is admitted to the cylinder *a* behind the piston the piston-rod is caused to move forward and through the lever *E* and connecting-rod *F* to apply the brakes, as shown in dotted lines in Fig. 1. The rod *D* is provided with an eye at its rear end, to which may be attached the front end of the rod *B* in the forward car. Each car in the train is of course provided with the same apparatus.

In order to adapt our invention for use as a

hand-brake, we attach the chain *H* to the lever *C*, and connect it to the ordinary lever, ratchet, and pawl on the platform of the cars or on the tender, and thus enable the cars to be checked by brakemen, as in the ordinary way. The cylinder *a* is supplied with steam by the pipe *A*, leading from the steam-dome, the pipe extending along the upper side of the cylinder and connecting therewith at the rear end, as at *f*, so as to admit the steam behind the piston. This pipe *A* is also connected to the cylinder *a* at the front end by means of the angle-pipe, *g*, which has the valve-socket *h*, in which plays the valve *i*, the valve being operated by means of the bell-crank lever *k*, pivoted to the cylinder-head at *l*, the depending arm *m* of said lever being pivoted to a tappet-rod, *n*, which extends through the cylinder-head and rearward a suitable distance into the cylinder. The valve *i* is normally closed, steam being only admitted through the opening *f*. When applying the brakes the piston moves forward, and should a break occur the piston, relieved of its rearward resistance, would rush violently forward and knock out the cylinder-head, were it not for the mechanism just described; but when our improvement is used the piston comes in contact with the tappet-rod *n*, and through it and the lever *k* opens the valve *i*, thereby admitting steam into the front end of the cylinder, and thus causing an equal pressure to bear upon the piston at both sides. This feature is of very great importance, as will be readily understood. Secured to each end of the cylinder *a*, at the lower side thereof, are the valves *o*, which are kept normally open by the springs *p* bearing against their undersides, as shown. The springs are in practice so constructed as to bear a pressure of five (5) pounds to the square inch. When steam is in the cylinder above that pressure the valves are closed. When below it they are open, and the water which results from the condensation of the steam is allowed to escape from the cylinder.

Having thus described our invention, we claim—

1. The system of brakes herein described, composed of the rod *B*, lever *C*, pivoted thereto, rod *D*, lever *E*, secured to the rod *B* at its upper end, fulcrumed to one set of brakes and having its lower end pivoted to the connecting-rod *F*, connecting-rod *F*, and suitable

brakes, in combination with the cylinder *a*, secured to the locomotive, the said cylinder being provided with the pipe *A* for admitting steam to the rear end, pipe *g* for admitting steam to its forward end, said pipe *g* being provided with a valve, *i*, suitable lever, *k*, and tappet-rod *n*, projecting into the cylinder, and having a piston-rod and piston working therein, all combined and arranged to operate substantially as shown and described.

2. The cylinder *a*, provided with the pipe *A* for admitting steam to its rear end, pipe *g* for admitting steam to its forward end, said pipe *g* being provided with a valve, *i*, suitable

lever, *k*, and tappet-rod *n*, projecting into the cylinder, in combination with the piston and rod working thereon, whereby accident to the cylinder may be prevented by causing the valve *i* to be opened, and steam admitted to both sides of the piston in case of a break, substantially as shown and described.

In testimony whereof we have hereunto set our hands this 21st day of December, A. D. 1882.

FRED. B. WALKER.
WITNESSES: JAMES LAUDER.
